(57) **CLAIM**

The ornamental design for a support arm, as shown and described.

DESCRIPTION

FIG. 1 is a perspective view of my support arm;
FIG. 2 is a front view of my support arm;
FIG. 3 is a first side view of my support arm;
FIG. 4 is a second side view of my support arm;
FIG. 5 is a top view of my support arm;
FIG. 6 is a bottom view of my support arm; and,
FIG. 7 is a rear view of my support arm.
The portions of the support arm shown in broken lines form
no part of the claimed design.
